RICHARD D. GALLAGHER, JR., OF NEW YORK, N. Y., ASSIGNOR TO STANDARD COUPLER COMPANY, OF NEW YORK, N. Y., A CORPORATION OF NEW JERSEY.

BUFFING MECHANISM FOR RAILWAY-CARS.

971,985.

Specification of Letters Patent.

Patented Oct. 4, 1910.

Application filed May 25, 1909. Serial No. 498,321.

To all whom it may concern:

Be it known that I, RICHARD D. GALLAGHER, Jr., a citizen of the United States, residing at New York, in the county of New York and State of New York, have invented certain new and useful Improvements in Buffing Mechanism for Railway-Cars; and I do hereby declare the following to be a full, clear, and exact description of the same, reference being had to the accompanying drawings, forming a part of this specification, and to the figures and letters of reference marked thereon.

This invention relates to buffing mechanism for railway cars, and more especially to railway passenger cars in which the buffer is adapted to conform to the movements of the coöperating buffer so as to maintain their parallelism while the cars are rounding curves.

The objects of the invention are to provide a simple, strong and highly efficient mechanism in which the outward movements of the buffer will be limited while permitting of a wide range of angular movement with respect to the car body.

A further object of the invention is to provide means for supporting and retaining the buffer springs and coöperating parts which means shall also serve as a strengthening means between the buffer beam and end sill of the car.

Referring to the accompanying drawings; Figure 1 is a top plan view of a portion of the framing of one end of a passenger car, partly in section, embodying features of construction relating to the present invention; Fig. 2 is a vertical section on the line 2—2 Fig. 1; Fig. 3 is a vertical section on the line 3—3, and Fig. 4 is a section on the line 4—4 of Fig. 1.

Similar letters of reference indicate like parts in all the views.

The letter A indicates the end sill of a car which may be of any preferred construction, B the buffer beam and C the buffer beam extension. The buffer beam extension is preferably of malleable iron. It is secured to the front face of the buffer beam and provided with bearings at the center and sides, respectively, for the center and side stems of the buffing mechanism. As illustrated, sills D of I-beam con-

struction extend longitudinally of the car beneath the end sill and buffer beam, although any preferred or well known platform and car frame timbers or sills may be employed.

Between the end sill A and buffer beam B there are arranged, in accordance with the present invention, three housings, preferably separate from each other and each formed in halves with an internal chamber or compartment for the reception of the buffer springs and associated parts. These housings are indicated by the reference letters E and F and, as shown, they are preferably of such length as to abut at their ends against the proximate faces of the end sill and buffer beam, whereby the latter parts are rigidly supported one by the other, thereby greatly strengthening the structure. By forming the housings in integral halves longitudinally any one or more of them may be readily opened by removing the connecting bolts f so as to give access to the buffer springs, etc. In practice, the said housings may be conveniently supported directly on the upper faces of the I-beams or longitudinal sills of the car by means of flanges e, best seen in Fig. 4 of the accompanying drawings.

As will be seen from Figs. 2 and 3, the inner face of the buffer beam is provided with an angle-iron G, the lower flange of which forms practically a continuation of the lower wall of the under half of the housings. The said housings abut against the angle iron, as best seen in Fig. 1, although, as will be readily understood, it may be entirely omitted.

The center stem H is pivotally connected by a T-head h with the center of the buffer I and passes rearwardly through the buffer beam extension and buffer beam. Its rear end is connected by a bolt k with a follower or spring socket K working in the front end of the center housing and adapted by contact with the rear of the buffer beam to limit the outward movement of the center stem and buffer without limiting its capacity to swing horizontally about the end of the center stem so as to accommodate itself to the movements of the car bodies in rounding curves.

rear of the spring follower or socket K are a pair of buffer springs, one lettered L, being a relatively light spring well adapted to absorb light strains and to permit the 5 buffer to retreat under relatively light pressure until coupling is effected, and the other lettered L' being a relatively heavy spring adapted to absorb the main shocks and jars after the coupling is effected. To separate 10 the springs and limit the closing movement of the same a follower M is interposed between the springs, said follower having stems m within the springs, which stems serve as stops when the springs are driven 15 back until substantially closed.

The arrangement of the side stems N is somewhat different from that of the center stem in that they are free and under constant tension of light springs tending to 20 force the buffer outwardly beyond the limit permitted by the center stem but, being located on opposite sides of center stem counter-balance each other and each becomes effective in forcing the buffer outwardly 25 only when the opposite side stem is pushed inward against the greater resistance of other springs. Each side stem is, at its inner end, provided with shoulders which coöperate with spring followers when the 30 stem is pushed inwardly but the said stems are free to move outwardly and the shoulders move out of engagement with the spring followers in succession.

Referring particularly to Fig. 1, it will be 35 seen that each side stem is provided with shoulders n adapted to engage the spring follower O and with shoulders n' adapted to engage the spring follower O'. Relatively light springs o and o', respectively, 40 coöperate with the spring followers O and O', both of said springs abutting against an intermediate follower P and between said follower and the rear end of the housing there is located a relatively heavy spring P'. 45 All of said springs are preferably capable of long expansion so as to effectually maintain the pressure on the buffer throughout a wide range of movement.

With the buffer in its normal position, 50 the followers O' rest against the front ends of the barrels or rear of the buffer beam, the portions of the latter adjacent the stems, thus constituting stops which limit the outward movement of the followers O' and expansion of the outer side stem springs o' 55 but the stems may continue to move outwardly and the inner springs o and springs P' acting through the follower O will still continue to exert outward pressure. At 60 their forward ends, the side stems N may also be connected with the inner face of the buffer as by projections N' coöperating with sockets in a casting N² on the inner face of the buffer.

65 In operation, outward movement of the

buffer at the center is limited by the center stem, but outward movement of the ends of the buffer is limited only by the range of angular deflection possible before the ends of the buffer contact with the buffer beam 70 or buffer beam extension, the necessary movement of the ends of the side stems with relation to the buffer being made possible by elongating the sockets in the casing N², as shown by the dotted lines N³ in Fig. 1 75 of the drawings. In order to permit of the ready removal of the buffer without taking down or separating the housings or spring barrels, the bolt k may be removed through the openings k', after which the buffer, 80 together with its three attached stems, may be drawn out or away from the end of the car, leaving all the remaining parts of the apparatus in position ready for the reception of the buffer stems when they are again 85 returned to their places.

The relatively light springs not only serve to keep the buffers of adjacent cars in contact, but they permit of an easy resilient movement of the buffer to the point of coupling after which yielding resistance to further movement is greatly augmented by the action of the relatively heavy springs. 90

The buffer beam extension C and the casting N² will form ultimate stops for limiting 95 inward movement of the buffer and will, by their engagement, prevent disastrous deformation of any of the lighter parts when subjected to excessive buffing strains.

It will be observed that when the parts 100 are in normal position, as shown in Fig. 1, the buffer will stand at right angles to the longitudinal axis of the car and the inner side stem springs o alone exert outward pressure on the side stems as the followers 105 o' of the outer springs are limited in their outward movement by contact with the buffer beam. Under these conditions the inner spring o on one side cannot push that end of the buffer out because such movement 110 is resisted by both the inner spring o and the outer spring o' on the opposite side and, hence, angular movement of the buffer can only take place when the resistance is overcome by inward movement of that end of 115 the buffer. This arrangement causes the buffer to stand at right angles to the longitudinal axis of the car even though the side springs do not exactly balance each other because the outer springs and their 120 followers O' being limited in their outward movement are only effective to resist inward movement from the normal position of the buffer. They resist any pivotal movement of the buffer away from its normal position 125 at right angles to the center stem and, hence, even though the springs on one side are longer or stronger than those on the other the buffer will still be held in proper normal position and at the same time the inner 130

springs will be under constant tension so as to take up any slack or looseness between the parts.

Having thus described my invention, what I claim as new and desire to secure by Letters Patent, is:—

1. In a buffering mechanism, the combination with the buffer beam and end sill, of the substantially cylindrical buffer spring 10 barrel formed in longitudinal sections and with the ends abutting the beam and sill respectively, supporting flanges integral with said barrel, a spring confined in the barrel, a buffer and a stem for advancing 15 the buffer extending through the beam and into the front end of the barrel to coöperate with the spring.

2. In a buffering mechanism the combination with the buffer beam and end sill, and 20 angle iron in rear of and resting against the beam, of the independent substantially cylindrical buffer spring barrels formed in longitudinal sections and with their ends abutting the end sill and angle iron on the 25 beam whereby the beam is reinforced, transversely extending supporting flanges integral with said barrels, springs confined in the barrels, a buffer, stems for advancing the buffer passing through the beam and into 30 the front ends of the barrels, and followers interposed between the stems and springs.

3. In a buffering mechanism, the combination with the buffer beam, buffer, center stem and side stems, of independent springs for 35 advancing the center and side stems, a stop for limiting the outward movement of the center stem, stops for limiting the outward expansion of one of the side stem springs on each side when the buffer is at right 40 angles to the axis of the car, and other springs coöoperating with the side stems and

tending to move them outward after the expansion of the first-mentioned side stem springs has been arrested.

4. In a buffering mechanism, the combination with the buffer beam, buffer, center stem 45 pivotally connected with the buffer and means for limiting the outward movement of the center stem and center of the buffer, of the side stems coöperating with the buffer 50 on opposite sides of the center stem, two springs coöperating with each side stem for resisting inward movement of the ends of the buffer and stops for limiting the outward expansion of one only of the springs coöp- 55 erating with each side stem when the buffer is in normal position at right angles to the axis of the car whereby inward movement of each end of the buffer is resisted by both springs and one spring normally tends to 60 move the buffer outwardly.

5. In a buffering mechanism, the combination with the buffer, center stem on which the buffer is pivotally mounted and means for limiting the outward movement of the 65 center stem and center of the buffer, of side stems pivotally connected with the ends of the buffer, springs coöperating with said side stems and normally under compression tending to push the ends of the buffer be- 70 yond its normal position at right angles to the center stem, and other side stem springs coöperating with the side stems to resist in- 75 ward movement, with stops for limiting the expansion of said last mentioned springs when the buffer is in normal position and at right angles to the center stem.
